UNITED STATES PATENT OFFICE.

FERNANDO ALONSO É YZAGUIRRE AND JULIO YZAGUIRRE VILLA, OF DUNDEE,
SCOTLAND.

SHOE-SOLE AND METHOD OF MAKING THE SAME.

1,236,244.

Specification of Letters Patent.

Patented Aug. 7, 1917.

Application filed January 24, 1916. Serial No. 73,875.

To all whom it may concern:

Be it known that FERNANDO ALONSO É YZAGUIRRE and JULIO YZAGUIRRE VILLA, subjects of the King of Spain, residing at Old 5 Glamis Road, off Clepington Road, Dundee, Scotland, have invented new and useful Improvements in Shoe-Soles and Methods of Making the Same, of which the following is a specification.

10 This invention relates to improvements in the manufacture of boots, shoes, sandals, slippers, or the like and also to improvements in soles for such articles. The improvements are particularly applicable to 15 that type of boots or shoes which have soles composed of a wound or lapped band or bands secured together by transverse sewing.

Heretofore in the manufacture of such soles, after the winding or lapping of the 20 band or bands, the sole is sewn longitudinally or radially at the heel and toe and transversely along its whole length. The operation of sewing the toe and heel is costly, as, when done by hand, it is very slow and 25 laborious, and, when done by machine, skilled workmen are required as the operation is very intricate. Moreover a sole sewn at the heel and toe is flexible and has not sufficient rigidity at these parts. Again the 30 heel and especially the toe portion of a known sole is of too rounded a form, the longitudinal and radial sewing at these parts preventing the sole being pressed into an elongated shape to procure a sole with a 35 narrow rounded toe portion.

The object of the present invention is to obviate all the above mentioned disadvantages by providing means for securely closing the heel or toe portions without requiring 40 same to be sewn longitudinally or radially, and these means may at the same time be arranged to close the toe and heel portions of the upper.

According to the present invention the toe 45 or heel portion is closed by means of a fastening member, such as for example a spear-ended nail or the like, which when introduced into the sole is adapted to take and securely hold a binding thread or the like. 50 One, two or more fastening members may be employed. Preferably, the fastening member or members is or are arranged to engage with the end portions of the transverse stitching threads after same have been 55 crossed or knotted at the toe or heel. If de-

sired, however, a separate binding thread may be attached to one, two or more nails and secured in the sole. This latter method is especially suitable where the two ends of the threads of the transverse sewing are too 60 short to allow of same being crossed or knotted.

The toe and heel portions of soles produced according to the present invention are of greater strength and rigidity than the toe 65 and heel portions of the known soles. Again, according to the present invention, a sole with a narrow pointed toe can be easily obtained as the band or bands forming the toe portion are not pressed compactly 70 against each other in the longitudinal direction as is the case when they are sewn longitudinally or radially, so that, from an equal length of band, a longer or more elongated sole can be obtained by the present 75 invention than was heretofore possible. This has a monetary advantage as soles are sold according to their length or size. The main monetary advantage however lies in the low cost of the means for closing the 80 heel and toe and in the fact that the operation is simple and can be executed by unskilled workmen either by hand or machine.

As the binding threads have been introduced into the sole, the ends of the latter 85 present the same appearance as a sole which has been sewn at heel and toe. In the case where the upper is inserted between two lengths of the band or bands forming the sole and secured thereto by the transverse 90 stitching, the fastening means may also be employed to close the heel and toe of the upper in addition to closing the heel or toe of the sole.

In the accompanying drawings, Figure 1 95 illustrates in section a sole which has been transversely sewn, and Fig. 2 shows the same sole partly in section after the fastening members have been introduced into same. Fig. 3 is an enlarged end elevation of the 100 heel portion of Fig. 2. Fig. 4 is a section of a heel portion showing the application of the fastening members when the ends of the transverse threads are too short to be crossed or knotted. Fig. 5 illustrates various forms 105 of fastening members.

Referring to Figs. 1 to 5, the sole 1 is composed of a band 2 (see Fig. 4) wound in known manner, pressed, and transversely sewn along its whole length by means of two 110

threads 3 and 4. A series of soles are usually sewn one sole after the other in a transverse sewing machine, the soles being connected together by the threads 3 and 4. 5 These threads are cut at any convenient point, and the ends of the threads are crossed or knotted at the heel and toe as at 5, (see dotted lines in Fig. 1). Fastening members 6 (shown also in dotted lines in Fig. 1) are 10 now introduced into the heel and toe portions and these members are pressed into the sole as shown in Fig. 2. The fastening members 6, which may be of any convenient form or of any suitable material, are adapted to engage the end or ends of the transverse thread or threads and to pull these threads into the sole. Four convenient forms of fastening members are shown in Fig. 5, each member being provided with a cutting point 15 6^a, and with a thread retaining portion 6^b. The members are also formed with projecting portions 6^c which engage with the sole and prevent the member working out or from being withdrawn without damage to 20 the sole. The fastening members may be made of iron, steel, wood or any other suitable material. 25

Where the ends of the transverse threads are too short to allow of same being crossed or knotted, a separate thread or cord 7 may be secured in any suitable manner to two or more fastening members. Fig. 4 shows a thread 7 secured to three fastening members. 30

If desired, a separate cord may be attached to one, two or more members and after insertion, the free end or ends of same may be tightly knotted to the ends of the transverse threads. This modified method is not shown on the drawings but same will 40 be readily understood.

While one fastening member has been shown as applied to the toe portion and three fastening members as applied to the heel portion, it will also be readily understood 45 that any convenient number of fastening members may be employed either at the heel or at the toe, and that these members may be arranged in any desired manner. For instance, the fastening members have been 50 shown at the heel portion as inserted radially, but these may be inserted longitudinally or transversely if so desired.

In practice, the uppers A are sometimes secured to the sole by being inserted between 55 the two outer layers of the band 2 and sewn transversely at the same time as said layers. In such cases, the fastening members also serve to close the heel and toe portions of the uppers in addition to closing the heel 60 and toe portions of the soles. Where in other cases, the upper is secured to the sole by means of separate edge sewing, the fastening members may be pushed in sufficiently to leave a clear space for such edge 65 sewing.

We claim:—

1. A sole for boots, shoes, sandals, slippers or the like comprising a lapped band, a transversely stitched binding thread or threads securing the lapped portions together, and means introduced longitudinally through the side of the sole for securely fastening and stiffening the lapped portions at the extremity of the sole. 70

2. A sole for boots, shoes, sandals, slippers or bands and stitching to secure the lapped portions together and means for introducing and tightly securing the ends of threads of the transverse stitching within the sole at 80 the heel and toe, substantially as described. 75

3. A sole for boots, shoes, sandals, slippers or the like comprising a lapped band or bands, transverse stitching threads to secure the lapped portions together and means for 85 completing the seam of the sewing and closing the heel and toe and stiffening the same, substantially as described. 85

4. A sole for boots, shoes, sandals, slippers or the like comprising a lapped band, a plurality of threads sewn transversely, said threads being crossed or knotted at an end portion of the sole, and a rigid member having a retaining portion to engage said threads and introduce same into the sole. 90 95

5. A sole for boots, shoes, sandals, slippers or the like, comprising a lapped band, a plurality of threads sewn transversely, said threads being crossed at one end portion of the sole, and a nail having a barbed point 100 and a bent-over end, said threads being engaged by said bent-over end and introduced therewith into the sole. 105

6. In the manufacture of soles for boots, shoes, sandals, slippers or the like, the 105 method of closing the laps of the extremity of the sole by introducing a binding thread by means of a substantially unwithdrawable member.

7. In the manufacture of soles for boots, 110 shoes, sandals, slippers or the like wherein a band is wound into the shape of a sole and sewn transversely, the method of finishing the extremity of the sole by crossing the binding threads at such extremity, introducing them into the sole and knotting them, 115 substantially as described.

8. In the manufacture of soles for boots, 120 shoes, sandals, slippers or the like, wherein a band or bands is or are wound in the shape of a sole and sewn transversely, the method of securing the threads consisting in introducing a separate binding thread into the sole by a retaining member, and subsequently tightly knotting the same to the end 125 or ends of the thread or threads of the transverse sewing, substantially as described.

9. In manufacturing soles for boots, shoes, 130 sandals, slippers or the like wherein a band or bands is or are wound into the shape of

a sole and sewn transversely, the method of tightening the binding threads by introducing into the sole at its extremity a plurality of retaining members to tightly draw said binding thread round the edges of the sole, substantially as described.

5 In testimony whereof we have signed our

names to this specification in the presence of two subscribing witnesses.
